UNITED STATES PATENT OFFICE

RALPH MENOTTI, OF CHICAGO, ILLINOIS, ASSIGNOR OF THIRTY PER CENT TO JOHN SILVESTRO AND THIRTY PER CENT TO ACHILLE MENOTTI, BOTH OF CHICAGO, ILLINOIS.

FUEL LIGHTER.

Application filed December 26, 1924. Serial No. 757,998.

To all whom it may concern:

Be it known that I, RALPH MENOTTI, a citizen of the United States, and a resident of the city of Chicago, county of Cook, and 5 State of Illinois, have invented certain new and useful Improvements in a Fuel Lighter, of which the following is a specification.

My invention pertains to a fuel lighter, and more particularly to a device for lighting solid fuel, like coal, in a stove; and this 10 invention has for its object to provide means for igniting coal and similar solid fuel in a stove speedily and without dirt or labor, in order to avoid the usual trouble of finding and using kindling, etc. Another 15 object is to provide a fuel lighter with means for housing and protecting it from the ashes. And another object is to provide means for operating the fuel control valve 20 or gas valve and the protecting housing simultaneously to make both operative or inoperative at the same time.

Other objects will appear hereinafter.

The invention consists in the combinations 25 and arrangements of parts herein-after described and claimed.

The invention will be best understood by reference to the accompanying drawings forming a part of this specification, and in 30 which,

Fig. 1 is an elevational view of a stove showing my invention applied thereto;

Fig. 2 is an enlarged vertical sectional view showing my invention in position on 35 the stove;

Fig. 3 is a vertical cross sectional view taken on line 3—3 of Fig. 2;

Fig. 4 is an enlarged vertical cross sectional view taken on line 4—4 of Fig. 2;

40 Fig. 5 is an enlarged cross sectional view similar to Fig. 4, but showing the housing in its operative position with the opening or slit extending upwardly; and

Fig. 6 is a partial plan view of the burner 45 and its housing in the position shown in Fig. 5.

In the drawings, I have shown my invention in connection with a stove 10 provided with a fire pot 11 having a grate 12 with 50 the usual air inlet openings 13 at the lower end for supporting solid fuel, as coal or the like, thereon, said grate being supported on a cross rod 14 and lugs 15 provided in the stove.

55 The particular form of my invention dis-

closed, comprises a burner 16 provided with perforations or outlet openings 17, and preferably tubular in form, which is mounted at one end with a pin or member 18 in a bracket arm 19 secured to the stove, and the 60 other end of said burner is supported in a head 20 provided in a protective housing 21, preferably tubular in form, which is supported in a wall of stove 10. An outlet opening or slit 22 is provided on said housing, being registerable with the perforations 17 on the burner. A head 23 is provided in the end of said housing opposite head 20, for rotatably supporting said end 65 of the housing on the burner. 70

A fluid fuel conduit or gas conduit 24 is provided, which is supported with any suitable means, as a bracket 25 attached to the stove, and said conduit extends to an air regulating member 26 attached to the outer 75 end of burner 16, a valve 27 being interposed in said conduit 24, and having a stem portion 28 projecting from its upper end.

I provide means for operating the covering or housing 21 and the valve 27 simultaneously, said means comprising a gear 29 fastened to a collar 30 secured upon the outer end of housing 21, said collar and a collar 31 being adapted to hold the housing 80 against longitudinally sliding on the stove 85 and burner. A gear 32 engages and operates gear 29 and is mounted upon one end of a shaft 33, which is journalled in arms 34 extending from a bracket arm 35 secured to the stove, as with bolts 36 or 90 the like. A pinion 37 is fastened to the outer end of shaft 33 and is operated by a gear 38 secured to a stem 39 extending from the valve stem 28 and held in position by the bracket arm 35. A handle 40 is secured 95 with a crank arm 41 on valve stem 28 for turning gear 38 and thereby gear 29 and the connected housing 21, simultaneously with the turning of the valve, so that the housing will be turned with its slit 22 downward 100 to protect the perforations in the burner at the same time that the valve is closed, and so as to turn said slit 22 upwards in register with perforations 17 when the valve is open.

It is apparent from the above disclosure 105 that I have provided a convenient and efficient fuel lighter whereby solid fuel, such as coal within the fire pot may be readily ignited and fully started within a few minutes, thereby avoiding the necessity and 110

trouble of finding and using kindling, shavings, paper, etc., which usually causes dust, dirt, etc., around the stove and the room.

While I have illustrated and described the 5 preferred form of construction for carrying my invention into effect, this is capable of variation and modification without departing from the spirit of the invention. I, therefore, do not wish to be limited to the 10 precise details of construction set forth, but desire to avail myself of such variations and modifications as come within the scope of the appended claims.

Having described my invention, what I 15 claim as new and desire to secure by Letters Patent is:

1. In a stove having a fuel grate, a gas burner with perforations mounted beneath said grate, a valve for said burner, and 20 means for simultaneously actuating said valve to turn off the gas to said burner and for covering the perforations in said burner.

2. In a stove having a fuel grate, a fluid fuel burner with fuel openings mounted stationary underneath said grate, and housing 25 means movable to uncover said openings for use of the burner and having a closed portion movable over said burner openings to protect said burner and openings from 30 ashes.

3. In a stove having a grate, a fluid fuel burner mounted beneath said grate, covering means for said burner, a valve controlled feed conduit leading to said burner, and 35 means for simultaneously closing the valve and moving said covering means over said burner.

4. In a stove having a grate, a gas burner with gas outlets mounted beneath said grate, and a housing adapted to cover the top and the sides of said burner, said housing having an opening and being movable to register the same with said gas outlets for use of the burner.

5. In a stove having a grate, a tubular 45 burner with perforations mounted beneath said grate, a tubular housing with a longitudinal slit, and means for moving said housing to cover and protect said perforations and burner or to expose said perforations through said slit.

6. In a stove having a grate, a gas burner beneath said grate, a housing to cover said burner and protect it from ashes, said housing being movable to expose said burner for use, a gas conduit with a control valve attached to said burner, and operating means for closing said valve and covering said burner with said housing.

7. In a stove having a grate, a perforated tubular gas burner mounted underneath said grate, a tubular housing to cover said burner and having a slit registerable with said perforations, an inlet conduit connected to said burner and having a control valve therein, and a handle connected to said control valve and provided with gear means to simultaneously close said valve and cover said perforations or to open said valve and turn said housing to register said slit with said perforations.

In testimony whereof I have signed my name to this specification.

RALPH MENOTTI.
